UNITED STATES PATENT OFFICE.

JOHN VAN DYKE, OF KALAMAZOO, MICHIGAN.

GAS-STOVE.

1,297,119.

Specification of Letters Patent. Patented Mar. 11, 1919.

Application filed September 13, 1917. Serial No. 191,172.

To all whom it may concern:

Be it known that I, JOHN VAN DYKE, a citizen of the United States, residing at Kalamazoo, Michigan, have invented certain new and useful Improvements in Gas-Stoves, of which the following is a specification.

This invention relates to improvements in gas stoves.

The main objects of this invention are:

10 First, to provide a gas stove which is adapted to be mounted on a wall or like support and is rigidly supported, and the wall or like support effectively protected from the heat of the stove and also from 15 spatterings from the articles cooked.

Second, to provide an improved gas stove which is simple and economical in structure and at the same time attractive in appearance.

20 Further objects, and objects relating to structural details, will definitely appear from the detailed description to follow.

I accomplish the objects of my invention by the devices and means described in the 25 following specification. The invention is clearly defined and pointed out in the claims.

A structure which is a preferred embodiment of my invention is clearly illustrated in the accompanying drawing forming a 30 part of this specification, in which:

Figure I is a perspective view of a structure embodying the features of my invention, mounted upon a wall, the wall being conventionally illustrated.

35 Fig. II is a front elevation.

Fig. III is a detail vertical section on a line corresponding to line 3—3 of Fig. II.

Fig. IV is a detail perspective view of a 40 structure embodying my invention, the same being adapted for a single burner.

Fig. V is a detail front view of the embodiment shown in Fig. IV.

In the drawing, similar reference characters refer to similar parts throughout the 45 several views, and the sectional views are taken looking in the direction of the little arrows at the ends of the section lines.

Referring to the drawing, 1 represents a wall or like support on which my improved 50 stove is mounted. I provide a combination body and wall shield member 2 which is formed with a series of angles or steps. The body member is preferably formed of sheet metal, which may be readily enameled 55 or finished as desired. The body is provided with a top horizontal portion 3 to which the

wall attaching brackets 4 are secured by means of the stove bolts 5. These wall attaching brackets are angled, their horizontal legs being arranged under the top portion 3. 60 The vertical legs of the bracket are adapted to receive attaching screws 6.

In the structure shown in Fig. I, I provide a pair of grid members 7 having rearwardly projecting attaching brackets 8 65 which are lapped upon and secured to the intermediate portion 9 of the body member. The burners 10 are secured upon the under side of these grid members. The burner members are provided with oppositely disposed burner tubes 11 of the Bunsen type having inlet openings 12 and control valves 13. The burner tubes are connected by the T-coupling 14. The gas delivery pipe 15 is connected to this T-coupling 14 and has a 70 T-coupling 16 therein to which the gas supply pipe 17 is connected. At its lower end the gas delivery pipe 15 is provided with a wall attaching socketed plate 18 so that the delivery pipe serves as a supporting bracket 80 or face for the stove. The body members 3, in the structures illustrated in Fig. I, are provided with pan members 19 projecting from their lower edge, the pan members being spaced so that the pipe 15 may be disposed therebetween. 85

In the modification shown in Figs. IV and V but a single burner is provided. The gas delivery pipe 15 in this construction is connected directly to the burner tube, that is, 90 the coupling 14 is omitted. The valve 20 is mounted on the wall and the fuel supply pipe 21 leads therefrom to the coupling 16.

My improved gas stove is particularly advantageous for use in small kitchens and 95 kitchenettes or in rooms where the economy of space is an advantage. The structure when mounted is rigid, and secure and neat and attractive in appearance, the body member not only constitutes a support 100 for the grids and burners but serves as a shield to protect the wall from heat from the burner and also to a large degree from spatterings from articles cooked. The parts of my improved gas stove are simple and economical to produce and are readily assembled. 105

Having thus described my invention, what I claim as new and desire to secure by Letters Patent, is:

1. In a gas stove, the combination of a stepped body and wall shield member hav-

ing spaced pan portions projecting from its lower edge, wall attaching brackets secured to the top portion of said body member, a pair of grid members provided with attaching brackets secured to an intermediate portion of said body member so that said grid members are supported in a spaced relation above said pan members, a pair of burners secured on the under side of said grid members and having opposed burner tubes, a T-coupling connecting the adjacent ends of said burner tubes, and a rearwardly inclined gas delivery pipe disposed between said pan members and connected to said T-coupling, said delivery pipe being provided with a T-coupling for a gas supply pipe connection and with a wall attaching plate at its lower end so that when mounted on the wall the gas delivery pipe constitutes a supporting brace.

2. In a gas stove, the combination of a stepped body and wall shield member, wall attaching brackets secured to the top portion of said body member, a pair of grid members provided with attaching brackets secured to an intermediate portion of said body member, a pair of burners secured on the under sides of said grid members and having opposed burner tubes, a T-coupling connecting the adjacent ends of said burner tubes, and a rearwardly inclined gas delivery pipe connected to said T-coupling, said delivery pipe being provided with a T-coupling for a gas supply pipe connection and with a wall attaching plate at its lower end so that when the stove is mounted on the wall the gas delivery pipe constitutes a supporting brace.

3. In a gas stove, the combination of a stepped body and wall shield member having spaced pan portions projecting from its lower edge, wall attaching brackets secured to the top portion of said body member, a pair of grid members provided with attaching brackets secured to an intermediate portion of said body member so that said grid members are supported in a spaced relation above said pan members, a pair of burners secured on the under sides of said grid members and having opposed burner tubes, a T-coupling connecting the adjacent ends of said burner tubes, and a gas delivery pipe connected to said coupling.

4. In a gas stove, the combination of a sheet metal body and wall shield member having spaced pan portions projecting from its lower edge, and provided with wall attaching means, a pair of grid members secured to an intermediate portion of said body member so that said grid members are supported in a spaced relation above said pan members, a pair of burners secured on the under side of said grid members and having opposed burner tubes, a T-coupling connecting the adjacent ends of said burner

tubes, and a rearwardly inclined gas delivery pipe disposed between said pan members and connected to said T-coupling, said delivery pipe being provided with a T-coupling for a gas supply pipe connection and with a wall attaching plate at its lower end so that when the stove is mounted on the wall the gas delivery pipe constitutes a supporting brace.

5. In a gas stove, the combination of a sheet metal body and wall shield member provided with wall attaching means, a pair of grid members secured to an intermediate portion of said body member, a pair of burners secured on the under sides of said grid members and having opposed burner tubes, a T-coupling connecting the adjacent ends of said burner tubes, and a rearwardly inclined gas delivery pipe connected to said T-coupling, said delivery pipe being provided with a T-coupling for a gas supply pipe connection and with a wall attaching plate at its lower end so that when the stove is mounted on the wall the gas delivery pipe constitutes a supporting brace.

6. In a gas stove, the combination of a sheet metal body and wall shield member having spaced pan portions projecting from its lower edge, and provided with wall attaching means, grid members secured to an intermediate portion of said body member so that said grid members are supported in a spaced relation above said pan members, burners secured on the under side of said grid members, and a gas delivery connection for the burners disposed between said pan members.

7. In a gas stove, the combination of a stepped body member having a pan portion projecting from its lower edge, a wall attaching bracket secured to the top portion of said body member, a grid member provided with an attaching bracket secured to an intermediate portion of said body member so that said grid member is supported in a spaced relation above said pan member, a burner secured on the under side of said grid member, and a gas delivery pipe connected to said burner and constituting a supporting brace.

8. In a gas stove, the combination of a stepped body member, a wall attaching bracket secured to the top portion of said body member, a grid member provided with an attaching bracket secured to an intermediate portion of said body member, a burner secured on the under side of said grid member, and a gas delivery pipe connected to said burner and constituting a supporting brace.

9. In a gas stove, the combination of a sheet metal body member having a pan portion projecting from its lower edge and provided with a support attaching means, a grid member secured to an intermediate por-

tion of said body member so that said grid member is supported in a spaced relation above said pan, a burner secured on the under side of said grid member, and a gas delivery pipe connected to said burner and constituting a supporting brace.

10. In a gas stove, the combination of a stepped sheet metal body and wall shield member provided with a support attaching
5 means, a grid member mounted on said body member, a burner secured on the under side

of said grid member, and a gas delivery pipe connected to said burner and constituting a supporting brace.

In witness whereof, I have hereunto set 15 my hand and seal in the presence of two witnesses.

JOHN VAN DYKE. [L.S.]
